UNITED STATES PATENT OFFICE.

HERMAN N. HANZLIK, OF WONEWOC, WISCONSIN.

RAIL FASTENER AND PAD.

1,114,471.

Specification of Letters Patent.

Patented Oct. 20, 1914.

Application filed February 10, 1914. Serial No. 817,856.

To all whom it may concern:

Be it known that I, HERMAN N. HANZLIK, a citizen of the United States, residing at Wonewoc, in the county of Juneau and 5 State of Wisconsin, have invented new and useful Improvements in Rail Fasteners and Pads, of which the following is a specification.

The present invention relates to ties for 10 supporting railway rails, the primary object of the same being to provide a tie which is constructed either of plastic material or of metal and which does not embody a sufficient amount of elasticity to yield or give 15 when the wheels of the rolling stock pass thereover, with a cushion block, and novel means for sustaining the cushion block upon the tie, whereby the desired amount of flexibility will be afforded the tie and rails, so 20 that breakage of the tie or rails will be thus overcome.

Other objects and advantages of the device will appear as the nature of the invention is more fully understood, it being understood 25 that various changes may be made in the form, proportion and size without departing from the scope of the claims or sacrificing any of the advantages thereof.

In the drawings: Figure 1 is a perspective view illustrating one end of a plastic tie provided with my improved cushion member, and showing the means whereby the cushion member is sustained upon the tie and a rail retained upon the cushion 35 member, Fig. 2 is a similar perspective view but looking toward the bottom of the tie, Fig. 3 is a perspective view showing the block arranged upon the tie, the tie retaining and rail sustaining means being removed, and Fig. 4 is a perspective view of the elements embodying the cushion block retaining and rail securing means.

In the showing of the drawing I have 45 illustrated my improvement as applied to a plastic tie, but it is to be understood that the same is not to be thus restricted in its useful capacity, as the improvement may be applied with equal success upon metal ties, or if necessary upon ordinary wooden ties.

50 The tie is designated by the numeral 1, and as the same has both of its ends of a similar construction, and as the improvement, which is applied to the tie at both of the ends, is also of a similar construction

and arrangement, only one of the ends of the 55 tie has been deemed necessary to illustrate.

The tie 1 upon its upper face and adjacent its ends is formed with a transversely arranged substantially rectangular channel or recess which is indicated by the numeral 60 2, the same being adapted to receive the lower portion of a substantially rectangular cushion member or block 3, the said block snugly engaging with the walls formed by the said channel or depression, and the block 65 being of a sufficient thickness to permit of its upper face being arranged a suitable distance above the upper face of the tie 1. This block 3, upon its upper face, is provided with an angularly arranged depression 4, the same extending from one of its ends to the block adjacent its corners to the opposite end of the said block adjacent its diagonally opposite corners, and the said recess is of a sufficient depth to snugly receive 70 a connecting rod 5. The rod 5 has one of its ends provided with a head 6 and its second end threaded, as at 7.

The numerals 8 designate locking or anchor bolts, each of which being provided 80 with a head 9 which extends over one of its faces, and the shanks of the bolts, for the major portion of their lengths are preferably rectangular, the lower portions of the said shanks, however, being rounded and 85 threaded, as indicated by the numerals 10. The cross sectionally rectangular shanks of the bolts 8, at a suitable distance below their heads 9, are provided with openings 11 through which the rod 5 passes, the head 6 90 of the said rod 5 engaging with one of the bolts 8, and the threaded end 7 of the said rod which extends through the opening 11 in the second bolt 8 is provided with a retaining device in the nature of a nut 12. By 95 such an arrangement it will be noted that the bolts 8 may be retained adjustable upon the rods 5, and may also be brought into tight frictional engagement with the ends of the 100 block 3 as well as with the sides of the tie 1, and the heads 9 of the bolts are arranged a sufficient distance from the rod 5 to snugly engage with the upper faces of the base flanges 13 of a rail 14, the shanks of the said bolts contacting with the longitudinal 105 edges of the said base flange 13.

The numeral 15 designates a flat metallic plate for the anchor bolts 8, the said plate

being disposed diagonally upon the underface of the tie, in the same direction of the recess 4 of the block 3, and the said plate is provided centrally and at its opposite ends 5 with elongated slots 16 through which pass the threaded ends 10 of the bolts 8, while nuts 17 engage with the said threaded ends which project below the plate 15, and so effectively secure the bolts to the plate and 10 heads of the bolts into tight frictional engagement with the base flanges of the rails, the said nuts also forcing the connecting rod 5 downwardly of the recess 4 so that danger of the said rod contacting with the 15 underface of the rail 14 is prevented, and in this connection it should be stated that the recess 4 is comparatively deep, but not of a sufficient depth to impair the strength of the cushion block 3. The slots 16 may enter 20 from the ends of the plate 15, as illustrated in Fig. 4 of the drawing, or the said slots may terminate adjacent the said ends as illustrated in Fig. 2 of the drawings, and from the above description, taken in connection 25 with the accompanying drawings, the simplicity of the device as well as the advantages thereof will, it is thought, be perfectly apparent to those skilled in the art to which such inventions appertain without further 30 detailed description.

Having thus described the invention, what I claim is:

1. A tie having transverse depressions, a cushion block arranged within the depressions and projecting above the face of the tie, a rail supported upon the cushion block, anchor bolts having their heads to engage with the base flanges of the rails to the opposite sides of the rail, means for longitudinally adjusting the anchor bolts with relation to the rail and cushion block, a bottom plate having openings through which the ends of the anchor bolts pass, and adjust-

able securing elements arranged upon the said ends of the bolts and binding upon the 45 bottom plate.

2. A tie having a cushion block thereon, said block having its upper face provided with an angular recess disposed diagonally with relation to its corners, a rail upon the 50 block, vertically adjustable rail securing members disposed in contacting relation with the opposite faces of the ties and the diagonally opposite corners of the cushion block, means arranged within the recess of 55 the block for longitudinally adjusting the said securing means and for retaining the said means in contact with the block and with the tie, a plate upon the underface of the tie, and means for securing the rail and 60 block retaining means to the plate.

3. A tie, a rail supporting cushion block upon the tie, said block having an angular recess which enters from its upper face, a headed rod having a threaded end seated 65 within the recess, headed anchor bolts having openings engaged by the rod, a nut upon the rod adapted to engage with one of the said bolts to force both of the bolts into frictional engagement with the opposite 70 sides of the tie, a plate arranged upon the bottom of the tie, said plate having elongated openings through which the threaded ends of the anchor bolts extend, and another 75 for the threaded ends adapted to frictionally engage with the plate to adjust the said bolts vertically to force the heads into engagement with the base flange of the rail to the opposite sides of the said rail.

In testimony whereof I affix my signature 80 in presence of two witnesses.

HERMAN N. HANZLIK.
